(57) **CLAIM**

The ornamental design for a connection element for vacuum cleaner bag, as shown and described.

DESCRIPTION

FIG. 1 is a top left front perspective view of the connection element for vacuum cleaner bag showing my new design; FIG. 2 is a top right front perspective view thereof; FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a front elevational view thereof; and,

FIG. 9 is a top right front perspective view thereof with unclaimed environment.

Any broken lines in the drawings indicate portions which form no part of the claimed design.
